CLAIM

The ornamental design for an air pump, as shown and described.

DESCRIPTION

FIG. 1 is a perspective view of the air pump;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

Light and shade expressed on the surface in each view are for specifying the shape of the surface.

The broken lines depict portions of the air pump that form no part of the claimed design.

1 Claim, 7 Drawing Sheets
